MONOTYPE MACHINE COMPANY, OF PHILADELPHIA, PENNSYLVANIA, A CORPORA-
TION OF VIRGINIA.

MATRIX-HOLDER FOR TYPE-CASTING MACHINES.

1,307,671.

Specification of Letters Patent. Patented June 24, 1919.

Application filed November 30, 1918. Serial No. 264,817.

To all whom it may concern:

Be it known that I, MAURITZ C. INDAHL, a citizen of the United States, residing at Philadelphia, county of Philadelphia, and 5 State of Pennsylvania, have invented certain new and useful Improvements in Matrix-Holders for Type-Casting Machines; and I do hereby declare the following to be a full, clear, and exact description of the 10 same, reference being had to the accompanying drawings and the characters of reference marked thereon.

This invention relates to matrix holders for type-casting machines of the class well 15 known as manufactured by Lanston Monotype Machine Company, the general organization of which machines is illustrated in the United States Patent No. 625,998, dated May 30, 1899.

20 When a machine of this kind is equipped for composition, it is provided with a matrix case, holding a number of matrices, each provided at one end with a cone hole for centering the matrix in coöperation with 25 the centering pin of the machine and usually with a typographic character impression in the opposite end. It sometimes becomes desirable to cast sorts from a single matrix of this kind, and for this reason a matrix 30 holder has been devised for holding one only of these matrices this holder being adapted for use either when the machine is equipped for composition or when it is lacking certain elements necessary for composition 35 and is capable therefore of use merely as a sorts caster. An illustration of such a matrix holder may be found in U. S. Patent No. 1094628 dated April 28, 1914. A different kind of sorts matrix holder is often 40 employed for holding electro-matrices which are flat as compared with the cellular matrices above described, and are made by an electro plating process. A holder of the last mentioned kind is illustrated in Patent 45 No. 1193345 dated August 1, 1916. A feature of this electro-matrix holder as compared with the previously mentioned cellular-matrix holder is that the electro-matrix holder proper is adapted to be slidably 50 engaged with a sheath member which itself slides into the machine and is provided with a hook for attaching it to said machine. The first mentioned holder has this hook device attached to it rather than to a sepa- 55 rate sheath member. The holder of the present invention is adapted to hold cellular-matrices, but it is also designed in its more limited form, to have the sheath feature of the electro-matrix holder. When a casting or composing machine has the sheath 60 member secured in place, the machine is adapted for casting from a cellular matrix or from an electro-matrix, according to which matrix holder one may desire to insert into the sheath member. 65

The cellular matrix holders which have been employed heretofore have been capable of holding only a matrix of definite dimensions, or at most matrices of a limited number of special dimensions. The present invention has for its object the production of a matrix holder of this kind which shall be easily adapted for holding matrices of a variety of sizes. It consists, generally speaking, of a main member or frame equipped 70 with a handle, such member being slideable into the machine, or preferably, into the above mentioned sheath secured in the machine, in which main frame there is a matrix retaining supplemental frame, so supported in the main frame as to be readily removed from the main frame as a whole and substituted by another supplemental frame adapted to retain matrices of a different size. The removal of the supplemental frame from the main frame is a simple matter since it is accomplished preferably by merely removing a locking device. The invention also contemplates the making 75 of a holder embodying a frame of a plurality of members, one of which contains a cell for retaining the matrix, and one of which members also is easily movable to a position in which the matrix may be readily extracted, such movement to matrix extracting position being accomplished without necessarily removing the supplemental frame as a whole from the main frame. The movement of a member of the supplemental frame to matrix extracting position is designed to 80 be even more simple than removal of the supplemental frame entirely from the main frame; the matrix extracting position being 85 one, which must be assumed very often in casting from matrices of the same external 90 size, it being readily observed that the change from one matrix to another of the same size is a frequent one as compared with 95 100 105

the change from one size of matrix to another size, the latter being such as to require the removal of the supplemental frame from the main frame.

5 In the accompanying drawings, illustrating a preferred form of matrix holder embodying the invention,

Figure 1 is a plan view of the holder;

Fig. 2 is a longitudinal section, on the 10 line 2—2 of Fig. 1;

Fig. 3 is a front end view of the holder; and

Fig. 4 is a plan view of a portion of the 15 holder equipped with a supplemental member, for retaining matrices of a different size from those of Fig. 1.

The main frame 5 of the holder consists of a plate like structure, provided with parallel sides equipped with side guides or ribs 20 6 adapted to fit in the guide ways of the sheath member above spoken of or of the usual die case frame of the composing machine. The frame is provided with a leaf spring 7 upset near its free end to form a 25 catch 8 and provided with a button 10 for engagement usually with the thumb when the handle 11 also attached to the frame is, as is usual, grasped with the right hand. The spring and its catch are so arranged 30 that in moving the holder into the machine the catch 8 will engage with a part of the sheath member so as to secure the main frame 5 in the machine with the matrix in proper position for casting. Depressing 35 the catch 8 by moving the button 10 down by the thumb will release the main frame from the sheath so that said frame may be readily withdrawn from the machine. The main frame is provided substantially centrally thereof with an aperture of generally rectangular shape to receive the supplemental frame.

The supplemental frame consists, as 45 shown, of two block like members 9 and 9^a, the member 9 thereof being provided with a matrix cell notched in a lateral edge thereof, such cell being of the dimensions to retain a matrix of a desired size; the second member 9^a of the supplemental frame 50 is adapted to abut against this edge of the first mentioned cell member 9 so as to close the open side of the cell thereof. Both members when thus positioned accurately fit the aperture in the main frame. A locking device in the form of a pin 12 is adapted to 55 pass through aligned holes in the members 9 and 9^a of the supplemental frame near one end thereof so that the latter is locked in the main frame. The cell member 9 of 60 the supplemental frame may be tilted upon this pin for example to a position shown in dotted lines in Fig. 2 which may be called the matrix extracting position, in which position the matrix may be inserted into 65 or extracted from the cell. The member

9^a of the supplemental frame is held from tilting, however, by having its rear end cut away to form a tongue 13 extending under and being retained by the end of the leaf spring 7, as is clearly shown in Figs. 1 and 70 4. The rearward ends of the supplemental frame members rest upon a shelf 14 extending from the main frame across the rear end of the aperture therein. There can be no downward tilting on the axis of pin 12 75 because of such seating of the rear ends of the supplemental frame members upon this shelf 14. The tilting member 9 of the supplemental frame is also provided with laminated plates 15 and 16 shown particularly 80 in Fig. 2 both plates being seated in a recess in the under side of said member 9 and being riveted thereto by the rivets 17. The lower plate 15 is provided with a notch corresponding with the matrix notch or cell in 85 the member 9 while the upper plate 16 has a smaller notch to correspond with the dimensions of the intermediate portions of the matrix, the latter being indicated by the character M; the plate 16 therefore serves 90 to retain the matrix from up and down movement in its cell. It is obvious that the matrix is adapted to be seated in the cell by being slid laterally thereinto when member 9 is tilted to the dotted position of Fig. 95 2. The pin 12 is provided with a knurled head and with a spring operated detent 18 the end of the detent engaging with the pin by seating in the groove 19 in the head thereof. A pull upon the pin 100 by the fingers will be sufficient to move the detent out of its groove and thus release the pin so that it may wholly or partially be withdrawn from the main frame to allow the supplemental frame to drop out of the 105 main frame. When the proper supplemental members have been placed in the aperture in the main frame pin 12 may be inserted by pushing it into the pin holes in the main and supplemental frames and the detent 110 will automatically seat itself in the groove 19 in the head of the pin so as to retain the pin in locking position and prevent its accidental removal.

When it is desired to use a matrix of different size from that for which the supplemental frame, shown in Fig. 1, is adapted, a different supplemental frame is employed, for example a supplemental frame such as is shown in Fig. 4, adapted for use with a 115 matrix M' of greater external dimensions than those of the matrix M of Figs. 1 and 2. The cell in the retaining member 9' of the supplemental frame (Fig. 4) is of suitable size to accommodate the matrix M': 120 Moreover since the side walls of this matrix are all located distances from the centering or cone hole m of the matrix which differ from the corresponding distances in the matrix M, and since the cone hole ob- 125 130

- viously must necessarily be similarly located for all sizes of matrices, the supplemental frame members 9' and 9^b may differ in lateral dimensions and in the size 5 and location of the matrix cell, although the width of the supplemental member over all corresponds in all cases with the width of the aperture in the main frame. For example the member 9' of Fig. 4 is wider than the member 9 of Fig. 1, while the member 9^b is correspondingly of less width than the member 9^a; moreover the cell for matrix M' differs in dimension and location from that for matrix M. It will readily 10 be observed that whatever size of matrix may be desired to be used, the present invention makes its fitting in the holder in accurate and proper location for casting a simple operation which cannot possibly 15 be accomplished improperly. The matrix to be used must fit the matrix cell and when the proper cell member has been found to fit the matrix the proper abutting member of the supplemental frame must be found, 20 else the supplemental frame will not fit into the aperture of the main frame; a mistake in assembling is therefore impossible.
- In Fig. 4 a modification is shown according to which a tubular extension 20 on the 25 cellular member 9' of the supplemental frame which extension is coaxial with the retaining pin 12, extends through member 9^b of the supplemental frame and is upset on its end so as to secure together the two members 9' and 9^b of the supplemental frame at 30 all times, although one may be tilted or moved to matrix extracting position without disturbing the other. When the two members are thus associated, it is of course impossible to mix or confuse the members of 35 supplemental frames. In this way a pair of members secured together forms a supplemental frame for a matrix of definite size and makes it impossible to make an erroneous 40 assemblage of supplemental members.
- When the matrix holder has been inserted into the machine and a sufficient number of 45 types have been cast from a given matrix, the holder is removed from the machine, and the matrix is extracted by merely tilting 50 the cell containing member of the supplemental frame to the dotted line position of Fig. 2 and withdrawing the matrix by sliding it laterally from its cell. A new matrix 55 of the same size may be laterally slid in the cell, the cell member allowed to fall back to normal position and the holder inserted into the machine. This change of matrices of the same size is obviously a quick and simple 60 operation. When it is desired to use a matrix of different size, the locking pin 12 is withdrawn and the supplemental frame is allowed to drop out. Another frame with a cell to accommodate the matrix is readily 65 placed in the main frame aperture, the lock-
- ing pin is replaced, the new matrix is inserted after tilting the cell containing member of the new supplemental frame and the holder is ready for insertion into the machine. The whole operation is readily accomplished in a manner which excludes the possibility of wrong assemblage or erroneous location of the matrix with respect to proper casting position.
- I claim:—
1. A matrix holder for typecasting machines comprising a main frame and a supplemental frame secured to and removable from said main frame, said supplemental frame comprising a plurality of members 70 one of which is provided with a matrix cell notched in one edge thereof and one of which is movable relatively to the other to permit of the insertion of the matrix into or its extraction from the cell.
  2. A matrix holder for the typecasting machines comprising a frame embodying a plurality of members one of which is provided with a matrix cell notched in one edge thereof and one of which is pivotally mounted 80 for movement relatively to the other to permit of the insertion of the matrix into or its extraction from the cell.
  3. A matrix holder for typecasting machines comprising a main frame provided 85 with an aperture, a supplemental frame supported within said aperture, said supplemental frame being provided with a matrix cell, a pin extending through the main and supplemental frames to lock them together 90 and a spring detent engaging with the pin to retain it in locking position.
  4. A matrix holder for typecasting machines comprising a main frame and a supplemental frame removably secured to said 95 main frame, said supplemental frame embodying a member provided with a matrix cell notched in one edge thereof and a second member abutting against said edge to close the open side of said cell, said cell containing member being movable relatively to said 100 cell-closing member to permit of the insertion of the matrix into or its extraction from the cell.
  5. A matrix holder for typecasting machines comprising a main frame provided 105 with an aperture, a supplemental frame supported within said aperture, said supplemental frame comprising a member provided with a matrix cell notched in an edge 110 thereof and a second member abutting against said edge to close the open side of said cell, a pin extending through the said main and supplemental frames to lock them together and a spring detent engaging with 115 said pin to retain it in locking position, said cell containing member being pivoted on the axis of said pin for movement to permit of the insertion of the matrix into or its extraction from the cell.

6. A matrix holder for typecasting machines comprising a main frame provided with an aperture and a supplemental frame embodying a member provided with a matrix cell notched in one edge thereof, said member being pivoted to the main frame within the aperture thereof, and said supple-

mental frame embodying a second member abutting against said edge of said cell containing member to close the open side of said cell, said second member being locked against pivotal movement. 10
